CLAIM

I claim the ornamental design for a sole for footwear, as shown and described.

DESCRIPTION

FIG. 1 is a perspective view of a sole for footwear in accordance with the new design.

FIG. 2 is a front view thereof.

FIG. 3 is a rear view thereof.

FIG. 4 is left side view thereof.

FIG. 5 is a right side view thereof.

FIG. 6 is a top view thereof; and,

FIG. 7 is a bottom view thereof.

The broken lines in FIGS. 2, 3, and 6 define the bounds of the claimed design, with the broken lines and top interior of the sole forming no part of the claimed design.

1 Claim, 7 Drawing Sheets
